(57) **CLAIM**

The ornamental design for a pet house and carrier, as shown and described.

DESCRIPTION

FIG. 1 is a perspective view of the top, front, and right side of a pet house and carrier showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a reference perspective view thereof showing the perch insert inside in a carrying mode; and,

FIG. 9 is an exploded perspective view of FIG. 1 showing the handles in a closed position for the ease of illustration.
